PALLET TIERING FRAME

Leroy F. Skubic, Long Beach, Ind., assignor to The Paltier Corporation, Michigan City, Ind., a corporation of Illinois

Filed Oct. 16, 1963, Ser. No. 317,402
10 Claims. (Cl. 108—53)

The present invention relates generally to pallets and load-supporting pallet tiering frames therefor, and more particularly to improvements in mounting brackets for mounting the frames on the pallets, and is a continuation-in-part of my application Serial No. 180,529, now abandoned.

It is an object of the present invention to provide a mounting bracket for a pallet tiering frame which will allow the frame to be quickly and easily installed on the pallet, while providing an unusually rigid interengagement which will allow the pallet and frame combination to be employed to the limit of their collective capabilities. It is a related object of the present invention to provide a mounting bracket as characterized above which is simple and durable of construction and, thus, highly economical to make and use.

It is another object of the present invention to provide a mounting bracket for a pallet tiering frame which is capable of securing the frame to the pallet against undesirable movement of the frame in any and all directions, thereby eliminating accidents and loss of time through inadvertent slippage, or otherwise unintended disengagement, of the frame from the pallet.

A further object of the present invention is to provide a mounting bracket as characterized hereinabove having an additional safety feature which permits the bracket to be securely locked in its engaged position, irrespective of whether solid decking or spaced deck boards are used on the associated pallet.

It is still another object of the present invention to provide a mounting bracket of the type described which may be selectively inserted into or permanently attachable to the frame itself, and which is compatible with various forms of frame interlocking arrangements so as to make the frame easily mountable, either separately or in one piece, and in either case requiring only a minimum of skill and strength to accomplish the mounting.

These and other objects and advantages of the present invention will become more apparent in the reading of the following detailed description when taken in connection with the accompanying drawings, wherein:

FIGURE 1 is a perspective view of one type of pallet tiering frame embodying the present invention;

FIG. 2 is an enlarged perspective view of a mounting bracket shown in FIG. 1, which illustrates one form of the invention;

FIG. 3 is a perspective view of another type of pallet tiering frame embodying the present invention;

FIG. 4 is an enlarged perspective view of an alternative mounting bracket, shown in FIG. 3, which illustrates another embodiment of the invention;

FIG. 5 is a perspective view of still another type of pallet tiering frame embodying the present invention;

FIG. 6 is an enlarged perspective of mounting bracket similar to that of FIG. 4, but embodying the alternative safety lock construction of the invention;

FIG. 7 is a partial section of the pallet and frame showing the arrangement of elements when the bracket of FIG. 6 is used; and

FIG. 8 is a section taken along the line 8—8 of FIG. 6.

While certain illustrative modifications of the present invention have been shown in the drawings and will be described below in considerable detail, it should be understood that there is no intention to limit the invention

2

to the specific forms disclosed. On the contrary, the intention is to cover all modifications, alternative constructions, equivalents and uses falling within the spirit and scope of the invention, as expressed in the appended claims.

The present invention is constructed to be universally mountable on most commercial pallets, whether single or double face, and without reference to the particular decking dimensions of the pallet, insofar as they are compatible with the type of frame to be mounted thereon. An exemplary pallet 10 is shown in FIG. 1 and includes the plurality of stringer members 11 which are serially spaced, and, as shown, are disposed endwise. Deck boards 12 may be nailed or otherwise fastened transversely of the stringers on either side thereof. By virtue of the present invention, it will be understood that solid decking consisting of a single platform may be used in place of deck boards where desired. For the purpose of simplicity, however, such structure is not specifically shown in the drawings. Where deck boards are placed on one side only, the pallet is referred to as single face, and where deck boards are placed on both sides of the stringers, the pallet is referred to as double face. In the exemplary pallet, a stringer is positioned at each end of the deck boards and one in the middle; however, the number of intermediate stringers may vary, depending upon the load which the pallet is intended to carry.

In order to increase the load-carrying versatility and ability of the pallet, there is provided a tiering framework attachable to the pallet for supporting a second pallet in vertically tiered relation to the first pallet. The particular framework construction will usually depend on the specific task to be performed. Appropriately, the present invention is adaptable to use with practically any pallet tiering frame, and, therefore, exemplary frames have been illustrated in FIGURES 1, 3 and 5. While the frames shown differ somewhat in their construction, they serve to illustrate the versatility of the present mounting bracket construction.

In FIGURE 1 there is illustrated an exemplary "square base" frame 15 well suited for supporting additional pallets without tipping due to uneven loading of other pallets mounted thereon. Broadly, the frame comprises a pair of U-shaped members 16 which are jointed by an interlock device 17. Frame posts or legs 20 are mounted in depending fashion from the bends of the U members 16. As illustrated, a hairpin or clevis-type mounting bracket 21 is provided at the foot of each depending frame post 20. The foot 21 is provided with a web 22 normal to the post upon which it is mounted, and from the web a pair of flanges 23 extend downward to straddle a portion of the stringer 11 showing between a pair of deck boards 12 near the middle of the stringer. Considering the frame 15 assembled as a whole, with the U members 16 interlocked, the posts 20 having the bracket or foot 21 described above are in substantially the same vertical plane, which plane runs parallel to the deck boards in the present instance and is located at approximately the midpoint of the base pallet.

The frame described is rectangular and, accordingly, includes another pair of legs or posts 25 disposed in a plane at right angles to the plane of the first-described legs 20. Secured to the base of each of these second-mentioned posts 25 is an improved mounting bracket 26 forming a part of the present invention in one of its exemplary embodiments. Viewing the invention in its broader aspects, a bracket is provided which embraces one edge of a deck board, preferably the outer edge thereof, and straddles the central, or one of the intermediate stringers, thereby gripping the pallet in a manner not unlike the manner in which one would grasp the outer deck boards with his hands.

With respect to the particular mounting bracket illustrated in FIGS. 1 and 2, there is provided a flat transverse web portion 30 which is secured in any convenient manner to the post, for example, such as by permanently welding to the lower end of the post. The web 30 in this instance has an upstanding insert over which the post is telescoped prior to welding. The insert is of such a size as to provide minimum clearance between it and the post so as to prevent sloppiness between the two. The web presents a substantially flat surface to the face of the deck board to which it is mounted, thus distributing the vertical components of the load experienced by that post over an area greater than that subtended by the diameter of the post.

For gripping the edge of the pallet deck boards, the bracket is provided, on the edge of the web outwardly of the area described by the four posts of the frame, with a pair of flanges 33 which extend downwardly from the web, and are formed at their lower ends with an inturned portion 34. The ends 34 are turned under and back so that viewing the bracket, as in FIG. 2, it has a J or hooked shape.

The bracket is conveniently formed by stamping or otherwise providing a substantially flat U-shaped configuration with an enlarged base, and then bending the legs of the U to form hooks, as seen in FIG. 2. The enlarged base portion, of course, serves as the web 30 of the bracket. The distance between the flanges 33 of the bracket is made only slightly greater than the thickness of the stringer 11 to minimize the possibility of lateral play when the bracket is mounted.

In keeping with an important aspect of the invention, a positive locking arrangement is provided which substantially eliminates any tendency of the legs carrying the improved brackets 26 from slipping outwardly, or in a direction away from each other. Such arrangement also prevents each bracket 26 from sliding away from its position embracing the deck board and straddling the stringer. To this end, a locking arrangement 36 is provided, which comprises, in one exemplary form, an aperture 37 in the web portion 30 of the bracket, which is aligned with a corresponding aperture (not shown) in the deck board and through the deck board into the stringer where deemed appropriate. A locking pin 38 is provided, which, for the purpose of the present invention, is illustrated as conveniently mounted to the post by a ring 39. The pin is disposed parallel to the post and, as the ring is moved downward along the post, the pin 38 passes through the hole 37 in the bracket and into the receptacle therefor provided in the deck board, thus creating a positive locking engagement between the bracket and deck board. The ring 39 can slide on the post, but loss of the pin is prevented inasmuch as the ring cannot be removed from the post.

When the frame is mounted to the pallet, the bracket is slipped over the deck board and positioned in the manner shown in FIG. 1 in straddling relation with the central stringer, and the locking pin 38 is inserted through the bracket into the pallet. In this manner, the bracket is not only mounted at a position of optimum strength of the pallet for carrying maximum loads applied to the frame structure, but slippage or other misalignment of the bracket, and consequently the posts secured thereto, is prevented. This is accomplished in part by reason of the inturned end portions 34 of the flanges which reside on either side of the stringer so that any tendency of the bracket to slide along the deck board 12 is prevented by the stringer, and in part by the engagement of the locking pins 38 with the brackets and the pallet. Because of the rigidity of the upper part of the frame as a result of the interlocking of the frame members, the entire frame is rigidly positioned on the pallet and capable of carrying optimum loads. Vertical loads on the frame are distributed on the flat web portions of the bracket, and non-

vertical loads are compensated for by the depending gripping flanges and the locking pins.

The wide applicability of the present invention becomes even more apparent when it is viewed with respect to the structure illustrated in FIGS. 3 and 4. For the purpose of easy comparison, parts of a nature and function comparable to those of FIG. 1 will bear similar numerals with a suffix "a" attached. In these figures, a modified framework is shown, which represents another well known pallet tiering framework. In the present example, a pair of H frames 45 are adapted to be mounted in the four corners of a pallet 10-a, which pallet is substantially identical to that shown in FIGURE 1. The H frame is conveniently interconnected by tubular crossbars 46 which have depending receptacles 47 for receiving the upper ends 48 of the corner posts 49 of the H frames.

At the foot of each corner post there is provided a mounting bracket 26a constructed in accordance with the present invention. The mounting bracket is secured to each corner post in any convenient manner, such as that shown in the previous figures. The bracket, however, though constructed in accordance with the principles of the present invention, is modified somewhat in order to make maximum use of the particular location in which it is to be used, that is, the corner of the pallet.

To this end, there is provided, as previously described, a flat webbed portion 30a which is in substantial face-to-face relationship with the face of the deck board to which it is mounted, and having flanges 33a, 33b depending therefrom, at least one of which, 33a, embraces the deck board 12a in a manner substantially as described heretofore.

In its present exemplary form, the flanges 33a, 33b depending from the web, lie in planes which are at right angles, thus providing support on both of the sides which come together to make the particular corner. Again, there is a space between the flanges which is greater than the width of the stringer member, in this case the end or outer stringer, so that the bracket may effectively straddle the stringer. As the deck boards are substantially flush with the outer side of each outer stringer, no inwardly extending portion is provided on the flange 33b which extends downward along this outer side. The other flange 33a is, however, provided with an inwardly turned or hooked end 34a and thereby embraces the deck board just inwardly of the end stringer.

A positive lock device 36a is provided and is substantially the same as the exemplary form illustrated in FIG. 1, comprising an aperture 37a in the web 30a and a complementary locking pin 38a to be received therein. The function of this locking device has been described in detail above.

With reference now to FIG. 5, still another exemplary pallet tiering frame is shown. Again, for purpose of easy comparison with previous embodiments, parts having a nature and function which are comparable in all of the views are, in FIG. 5, labeled with the appropriate numeral followed by the suffix b. Thus, in FIG. 5, there is shown a pallet tiering frame having an X configuration as defined by intersecting cross bars 55 and 56. Each end of the bars 55, 56 is fitted with a post receiving receptacle or cup 58 adapted to receive the upper ends of supporting posts 60. Each receptacle or cup 58 is conveniently provided with a set screw 62 for securing the posts on the X frame together.

Fixed to the lower end of each post, in a manner previously described, is a mounting bracket 26b, which resembles the bracket 26a in construction, and the brackets 26 and 26a in its function. The bracket 26b is adapted to mount the posts 60 at the four corners of the pallet 10b having stringers 11b and deck boards 12b or solid decking if desired.

The present invention encompasses a positive locking arrangement which inhibits lateral movement of the mounting bracket once in place. Such an arrangement is exemplified in FIGS. 2 and 4, and has been pre-

viously described. With reference now more particularly to FIGS. 6, 7 and 8 of the drawings, an alternative locking arrangement 62 is illustrated which affords security against not only lateral movement of the bracket as mounted to the pallet, but provides the additional valuable advantage of inhibiting inadvertent disengagement of the bracket and stringer by tipping or tilting thereof once the locking device is engaged. The locking arrangement 62 comprises, in its exemplified form, a vertically disposed locking pin 64, conveniently mounted by a ring 65 to the post 60, thus facilitating translation of the pin in a vertical direction guided by the post. An aperture 65 is provided in the web 30b of the bracket which is aligned with a hole of a slightly larger diameter formed in the pallet 10b passing through the deck board 12b and into the stringer 11b as seen in FIG. 7. It will be noted in FIG. 6 that in order to retain the locking pin at all times in a position of relative readiness for engagement with the pallet, a dimple 67 is formed on the post 60 a short distance above the bracket, thereby limiting movement of the ring 65 and accordingly the pin 64 on the post.

In keeping with this aspect of the invention, the locking pin 64 is formed with a protruding portion 70 intermediate the lower extremity of the locking pin and the elbow portion which attaches the same to the ring 65. As seen in FIG. 7, the protruding portion 70 presents a relatively flat shoulder or lip 72 to the underside of the web 30b when the pin is inserted in its locking position. It will be appreciated from viewing FIG. 7 that in the event that any tipping or tilting of the pallet tiering frame occurs the pin 64 will have a tendency to tilt slightly in the aperture provided therefor and the lip 72 will engage the underside of the web 30b, thus skewing the pin in its normal locking position and causing it to bear against the pallet within the hole. As a result, it becomes extremely difficult for the pin to inadvertently pop out or, in fact, be physically removed from its locking position as shown in FIG. 7 while the post 60 is tilted or tipped as before indicated. Accordingly, the pallet tiering frame and pallet remain engaged until the post 60 is again righted, at which time the pin 64 may be removed by pulling the same vertically outwardly to detach the bracket and pallet.

Thus, it is seen that a highly versatile mounting bracket is provided for attaching many different types of frame structures on conventional pallets in virtually any position.

I claim as my invention:

1. For use with a pallet having one or more deck boards transversely mounted on a plurality of stringer members, and a load-supporting framework on said pallet, said framework including posts extending vertically from said pallet where each is releasably mounted to a deck board, a mounting bracket comprising, in combination, a web attachable to a vertical post and disposable in face-to-face vertical load-supporting relation with a deck board, gripping flanges depending from said web, said flanges being so constructed and arranged as to embrace an edge of said deck board outwardly of said posts for supporting the same in position against nonvertical forces encountered thereby, means defining an aperture in said web, and a locking pin disposed for projection through said aperture into engagement with the deck board.

2. In combination, a pallet having a deck transversely secured to a plurality of stringer members, and a framework on said pallet, said framework including posts extending vertically from said pallet where each is releasably mounted to a deck by means of a mounting bracket, each said bracket including a web portion in face-to-face vertical load-supporting relation with said deck, and a plurality of gripping flanges depending from said web, at least one of said flanges being so constructed and arranged as to embrace an edge of said deck outwardly of said post for supporting said post in position against

nonvertical forces encountered thereby, and means including a member movable relative to said bracket for effecting a positive lock between said bracket and the associated deck of the pallet.

5 3. In combination, a pallet having serially spaced deck boards transversely secured to a plurality of stringer members, and a framework on said pallet, said framework including posts extending vertically from said pallet where each is releasably mounted to a deck board by means of a mounting bracket, each said bracket including a web portion in face-to-face vertical load-supporting relation with a deck board, and a plurality of flanges depending from said web having a space between them greater than the smallest dimension of said stringer, said flange substantially embracing an edge of said deck board in straddling relation with one of said stringers, outwardly of said post for supporting said post in position against nonvertical forces encountered thereby, and means including a pin member for effecting a positive lock between said bracket and the associated deck board of the pallet.

20 4. In combination, a pallet having a deck transversely secured to a plurality of stringer members, and a framework on said pallet, said framework including posts extending vertically from the corners of said pallet where each is releasably mounted to said deck by means of mounting brackets, each said bracket including a web portion in face-to-face vertical load-supporting relation with said deck, and gripping flanges depending from said web, such that the planes thereof are normal, and said flanges being so constructed and arranged as to embrace the corner of said deck outwardly of said posts for supporting the same in position against nonvertical forces encountered thereby, and positive locking means carried by said framework including aligned apertures in said web portion of said bracket and the associated deck, and a pin on said posts, receivable in said apertures for locking said bracket to the pallet.

25 5. In combination, a pallet having serially spaced deck boards transversely mounted on a plurality of stringer members, and a framework on said pallet, said framework including posts extending vertically from said pallet where each is releasably mounted to a deck board by means of a mounting bracket, said bracket including a web portion in face-to-face vertical load-supporting relation with a deck board, and gripping flanges depending from an edge of said web, said flanges being so constructed and arranged as to embrace the edge of said deck board outwardly of said posts for supporting the same in position against nonvertical forces encountered thereby, and means including a pin member movable relative to said web for effecting a positive lock between said bracket and the associated deck board of the pallet.

30 6. In combination, a pallet having serially spaced deck board transversely mounted on a plurality of stringer members, and a framework on said pallet, said framework including posts extending vertically from said pallet where each is releasably mounted to a deck board by means of a mounting bracket, said bracket including a web portion in face-to-face vertical load-supporting relation with a deck board, flanges depending from said web, inwardly extending fingers on at least one of said flanges, said flanges and said fingers cooperable to embrace the edge of said deck board outwardly of said posts for supporting the same in position against nonvertical forces encountered thereby, aligned apertures provided in said web and the pallet, a pin member slidably mounted outwardly of and parallel to said posts, said pin member being received in said apertures to prevent relative movement between said web and the pallet, a protrusion provided on said pin in position to engage the bottom of said web when an attempt is made to remove said framework from said pallet without first removing said pin.

35 7. In combination, a pallet having serially spaced deck boards transversely mounted on a plurality of stringer members, and a framework on said pallet, said framework including posts extending vertically from said pallet where each is releasably mounted to a deck board by means of a mounting bracket, said bracket including a web portion in face-to-face vertical load-supporting relation with a deck board, flanges depending from said web, inwardly extending fingers on at least one of said flanges, said flanges and said fingers cooperable to embrace the edge of said deck board outwardly of said posts for supporting the same in position against nonvertical forces encountered thereby, aligned apertures provided in said web and the pallet, a pin member slidably mounted outwardly of and parallel to said posts, said pin member being received in said apertures to prevent relative movement between said web and the pallet, a protrusion provided on said pin in position to engage the bottom of said web when an attempt is made to remove said framework from said pallet without first removing said pin.

7. In combination, a pallet having a deck transversely mounted on a plurality of stringer members, and a framework on said pallet, said framework including posts extending vertically from said pallet where each is releasably mounted to said deck by means of a mounting bracket, said bracket including a web portion in face-to-face vertical load-supporting relation with said deck, flanges depending from said web, inwardly extending fingers on at least one of said flanges, said flanges and said fingers cooperable to embrace the edge of said deck outwardly of said posts for supporting the same in position against nonvertical forces encountered thereby, aligned apertures provided in said web and the pallet, a pin member slidably mounted outwardly of and parallel to said posts, said pin member being received in said apertures to prevent relative movement between said web and the pallet, and a protrusion provided on said pin intermediate the ends thereof, defining a transversely extending lip, said lip adapted to engage the bracket to inhibit removal of said pin therefrom, when said pin is in other than vertical disposition.

8. In combination, a pallet having a deck transversely secured to a plurality of stringer members, and a framework on said pallet, said framework including posts extending vertically from said pallet where each is releasably mounted to said deck by means of a mounting bracket, each said bracket including a web portion in face-to-face vertical load-supporting relation with a deck, and a plurality of gripping flanges depending from said web, at least one of said flanges being so constructed and arranged as to embrace an edge of said deck outwardly of said post for supporting said post in position against nonvertical forces encountered thereby, and means for effecting a positive lock between said bracket and the associated deck of the pallet, including means for inhibiting removal of said positive means when the same is disposed in other than a vertical plane.

9. In combination, a pallet having serially spaced deck boards transversely secured to a plurality of stringer members, and a framework on said pallet, said framework including posts extending vertically from the corners of said pallet where each is releasably mounted to a deck board by means of mounting brackets, each said bracket including a web portion in face-to-face vertical load-supporting relation with a deck board, and gripping

flanges depending from said web, such that the planes thereof are normal, said flanges being so constructed and arranged as to embrace the corner of said deck board outwardly of said posts for supporting the same in position against nonvertical forces encountered thereby, and positive locking means carried by said framework including aligned apertures in said web portion and associated deck board, a pin on each of said posts receivable in said apertures, said pin having a protrusion thereon for inhibiting removal of said pin, and accordingly said bracket from said pallet when said pin is in other than vertical disposition.

10. In combination, a pallet having serially spaced deck boards transversely secured to a plurality of stringer members, and a framework on said pallet, said framework including posts extending vertically from the corners of said pallet where each is releasably mounted to a deck board by means of mounting brackets, each said bracket including a web portion in face-to-face vertical load-supporting relation with a deck board, and gripping flanges depending from said web, such that the planes thereof are normal, said flanges being so constructed and arranged as to embrace the corner of said deck board outwardly of said posts for supporting the same in position against nonvertical forces encountered thereby, and positive locking means carried by said framework including aligned apertures in said web portion of said bracket and the associated deck board, and a pin on each of said posts receivable in said apertures, and having means thereon for locking said pin in said apertures against removal when said framework is tilted or tipped on said pallet.
